FLOAT VALVE FOR POT TYPE OIL BURNERS

Alwin B. Newton, Oakwood, Ohio, assignor to
 Chrysler Corporation, Highland Park, Mich., a
 corporation of Delaware

Application May 27, 1946, Serial No. 672,495

4 Claims. (Cl. 137—400)

1

My present invention relates to means for controlling the flow of fuel oil to a burner of the vaporizing type. There are many types of oil burners which depend upon gravity feed for supply of fuel, the supply of fuel being adjustable from a maximum to a minimum quantity so as to have a small pilot flame and at least one controlled higher flame, in many cases there being a plurality of higher flame stages. There are many types of control devices for adjusting the flow of fuel, most of such devices comprising a chamber having an inlet valve under control of a float device adapted to maintain a substantially constant head in the chamber, and outlet means from the chamber comprising fixed orifices and needle valves which are opened or closed under control of various types of control means. It has been my observation that the means for opening or closing the valves are not dependable and give rise to numerous service complaints. Also the sizes of the orifices are usually so small that constant cleaning of the orifice or needle device controlling the orifice is necessary. It is an object of my invention to provide a fuel regulating device under control of a dependable type of control means, the device having only one large orifice which will not become fouled and which may permit the flow of any desired quantity of oil from a maximum to a minimum quantity, both extremes being adjustable.

It is a further object of my invention to provide an oil flow control device in which it is possible to use solid instead of hollow floats, thereby eliminating a constant cause of failure due to leaky floats.

A further object of my invention is to provide a flow control device having simplified automatic means for shutting off the flow of oil into the device in the event that the device becomes flooded due to failure of the oil to flow therefrom, such as would be caused by the inlet to an oil burner becoming clogged with carbon deposits. A further object of my invention is to provide an oil flow device having automatic dependable means for shutting off the supply of oil thereto regardless of the desires of the control means to continue the flow of oil thereto.

The foregoing and other objects and advantages of my invention will be readily apparent to those skilled in the art from an inspection of the following specification and accompanying drawings wherein like numerals refer to like parts throughout. In the drawings Fig. 1 is a vertical section through a preferred embodiment of my invention; Fig. 2 is a vertical section taken substantially

2

along line 2—2 of Fig. 1; and Fig. 3 is a vertical section taken substantially along line 3—3 of Fig. 1.

The flow control device comprises a vessel 12 divided by a vertical partition 13 to provide an inlet chamber 14 and an outlet chamber 15. The vessel is provided with a cover 16 suitably secured thereto and provided with an upwardly extending portion 17 having an oil inlet connection 18 therein. The outer end of the extension 17 is sealed off from the remainder thereof by a wall 20 providing a closed chamber within which is mounted a cylindrical strainer 21 held in position by a removable plug 22. Opposed to the plug is an outlet spud 23 having opposed valve seats therein adapted to be closed by a double acting valve 24 having a stem 25 attached thereto. When the valve is in the position illustrated flow of oil through the screen 21 and spud 23 is permitted but flow will be stopped upon movement of the valve in either direction to contact either of the valve seats. In order to cause movement of the valve the stem 25 is provided with a socket head 26 engaging the free end of a rocker lever 27 extending upward from a float carrying lever 28 pivoted at 29 to ears 30 extending downwardly from the cover 16. A solid float 31 is attached to one end of the lever 28 and extends into the chamber 14, and a counter-balancing solid float 32 is attached to the other end in chamber 15. The float 31 will rise and cause closing of valve 24 if chamber 14 reaches the overflow point and the float 32 will rise and cause closing of the valve if chamber 15 retains any appreciable quantity of oil.

The partition 13 is provided with an outlet orifice tube 35 at a predetermined level with respect to the desirable constantly maintained level of the fuel supply in chamber 14 so as to permit the flow of fuel therethrough under constant head. The tube 35 extends a short distance into chamber 15 and is inserted into the end of a flexible tube 36 of substantial length. The free end of the flexible tube carries a short length of rigid tube 37 which is received within the eye 38 of an eye bolt 39 which extends downwardly in chamber 15 and is adjustably secured to the free end of a bimetallic actuator 40 mounted on a boss 41 in the chamber 15. The position of the free end of the bimetallic element 40 thus determines the difference in level between the surface of the fuel oil in chamber 14 and outlet of tube 36. Thus means are provided for varying the total head tending to control the flow of oil into chamber 15.

Preferably the internal diameter of tube 35 is larger than the internal diameter of tube 37 so as to maintain the interior of the flexible tube 36 full of fuel oil.

The head acting against the outlet is controlled by means for adjusting the position of the bimetallic bar 40, the preferred form comprising a resistance heater element 45 positioned adjacent the bimetallic bar. The amount of current flowing through the resistance will vary the total heat radiated therefrom and hence vary the position of the bar. The resistance may be supplied with current by means of wires 46 and 47 leading from contacts 48 and 49, respectively, in the outer wall of the receptacle 12, the contacts having screw heads 50 and 51, respectively, to which may be attached wires leading from any suitable control means of which many possible types are known to the art.

The minimum flow of fuel oil may be adjusted by means of a screw 55 passing through an opening in the bar 40 and threaded into a boss 56 in the floor of the receptacle. The head of the screw is too large to pass through the opening, hence the bar will come to rest at a maximum height upon cooling.

The maximum flow of fuel oil may be regulated by means of a slide 57 having vertical slots 59 through which pass guiding rivets 60 extending inward from the end wall of the receptacle. The slide is provided with an upper inwardly extending portion 61 adapted to be engaged by an adjusting screw 62 carried by the cover 16, and is also provided with a lower inwardly extending portion 63 engaged by a compressed spring 64 extending between the extension and the floor of the receptacle so as to hold the slide firmly against the end of the adjusting screw. The free end of the bimetallic bar engages the extension 63 so as to adjustably limit the downward movement of the bar upon being heated, thus providing adjustable maximum flow.

If the burner is of the type requiring only minimum and maximum flow the controls may be such as to supply constant current to the heater 45 when maximum flow is desired. If the burner is of the type having several intermediate stages of combustion the amount of current flowing through the heater 45 may be regulated by suitable controls so as to tend to cause the bimetallic bar to rest at various intermediate levels.

The operation of the device may be commenced by means of a knob 70 extending above the cover 16 and attached to a vertically extending rod 71 having a horizontal arm 72 at its lower end. The knob 70 may be depressed and rotated to cause the arm 72 to engage the end of lever 28, which may then be lifted to cause valve 24 to open. The knob may be released as soon as sufficient oil has been admitted to chamber 14 to cause the valve to remain in open position. If the flow of oil through the valve 24 is faster than the flow from the chamber 14 the float 31 will rise sufficiently to move valve 24 to the left in Fig. 1 to shut the valve. The minimum flow of oil through the tube 36 will permit the lighting of a pilot flame in the burner which is connected by suitable means (not shown) to the outlet 75 from the chamber 15. If for any reason oil cannot flow through the outlet 75 the float 32 will be raised to shut off the flow of oil by moving the inlet valve 24 to the right in Fig. 1. Under normal operation the chamber 15 will be drained as rapidly as oil enters. The position of the tube 36 will be controlled by the amount and duration of current

flow through the heater 45 so as to control the flow of oil to the burner. If for any reason fuel should accumulate in chamber 15 and for some reason the inlet valve does not shut off due to the action of float 32, further safety means is provided in that the cooling effect of the oil accumulating around the bimetallic bar 40 will cause the tube 36 to be raised regardless of the influence of heater 45 to lower it, hence causing the level to rise in chamber 14 and causing the valve 24 to move to the left in Fig. 1 and shut off under control of the float 31.

Having illustrated and described a preferred embodiment of my invention it should be apparent to those skilled in the art that various modifications in detail and arrangement thereof are permissible within the scope of the following claims without departing from the spirit of my invention.

I claim:

1. A control device for regulating the flow of liquid fuel to a burner comprising a container having partition means defining a first and a second compartment therein, said container having an inlet to said first compartment and an outlet from said second compartment, a valve operable to close said inlet when moved in either of two directions and having an intermediate open position, said partition means having a discharge outlet connecting said first compartment and said second compartment, a flexible tube extending from said discharge outlet, control means to adjust the position of said flexible tube to control the flow of liquid from the first to the second compartment, a first float in said first compartment, means operably connecting said first float and said valve so that said valve is moved in a first direction to a closed position when said first float is raised above a predetermined level, a second float in said second compartment, means operably connecting said second float and said valve so that said valve is moved in a second direction to a closed position when said second float is raised above a predetermined level.

2. A control device for regulating the flow of liquid fuel to a burner comprising a container having partition means defining a first and a second compartment therein, said container having an inlet to said first compartment and an outlet from said second compartment, a valve operable to close said inlet, said partition means having a discharge outlet connecting said first compartment and said second compartment, a flexible tube extending from said discharge outlet, a bimetallic element operable to adjust the position of said flexible tube to control the flow of liquid from the first to the second compartment, electric heating device to control the temperature of said bimetallic element, a float in said first compartment and means operably connecting said float and said valve so that said valve is closed when said float is raised above a predetermined level by liquid in said first compartment, said electric heating device and said bimetallic element being positioned to be cooled by an accumulation of fuel in said second compartment to thereby elevate said flexible tube to decrease the flow of liquid fuel from said first compartment to said second compartment.

3. A control device for regulating the flow of liquid fuel to a burner comprising a container having partition means defining a first and a second compartment therein, said container having an inlet to said first compartment and an outlet from said second compartment, a valve op-

erable to close said inlet, said partition means having a discharge outlet connecting said first compartment and said second compartment, a flexible tube extending from said discharge outlet, a temperature responsive element operatively connected to said tube to lower said tube when said element is heated to thereby increase the flow of fuel between said compartments, control means to heat said element, said element being so positioned in said second compartment that the accumulation of an appreciable amount of fuel in said second compartment cools said element and decreases the flow of fluid from said first compartment, a float in said first compartment and means operably connecting said float and said valve so that said valve is closed when said float is raised above a predetermined level by liquid in said first compartment.

4. A control device for regulating the flow of liquid fuel to a burner comprising a container having partition means defining a first and a second compartment therein, said container having an inlet to said first compartment and an outlet from said second compartment, a valve operable to close said inlet when moved in either of two directions and having an intermediate open position, said partition means having a discharge outlet connecting said first compartment and said second compartment, a flexible tube extending from said discharge outlet, control means to adjust the position of said flexible tube to control the flow of liquid from the first to the second

compartment, a pivotally mounted control arm operatively connected to said valve, a first float in said first compartment connected to said arm on one side of its pivotal mounting, a second float in said second compartment operatively connected to said arm on the other side of its pivotal mounting whereby said valve is moved in a first direction to a closed position when the resultant of the forces acting on said floats rotates said arm in a first direction beyond predetermined limits and said valve is moved in a second direction to a closed position when the resultant of the forces acting on said floats rotates said arm in a second direction beyond predetermined limits.
